UNITED STATES PATENT OFFICE.

ELIOT S. STAPLES, OF IRON MOUNTAIN, MISSOURI.

ADDING MACHINE.

Application filed March 17, 1921. Serial No. 453,035.

To all whom it may concern:

Be it known that I, ELIOT S. STAPLES, a citizen of the United States of America, residing at Iron Mountain, in the county of 5 St. Francois and State of Missouri, have invented new and useful Improvements in Adding Machines, of which the following is a specification, reference being had therein to the accompanying drawings.

10 This invention relates to adding machines, and has special reference to that type of machines used by banks and similar institutions for adding and tabulating computations.

15 My invention, in its broadest aspects, involves utilizing digit apertures in lieu of characters or symbols and such digit apertures possess certain advantages in connection with an adding machine. First, it is 20 practically impossible to alter digit apertures and consequently a record or account represented by such digit apertures cannot be changed and any tampering with such a record can be easily detected. This feature 25 alone eliminates the nefarious practice of unscrupulous clerks in surreptitiously changing bank accounts and similar records. Second, the digit apertures constitutes a 30 matrix or template by which various instrumentalities are actuated and set for either duplicating or carrying forward matter for computing or tabulating purposes, and this 35 may be better understood by briefly considering the results attained by the machine.

35 By using my adding machine, one row of figures may be added to another row, for instance, a balance to a total. One set of digit apertures may represent the total and these digit apertures may be utilized for setting mechanism within the machine, prior to 40 operating the same mechanism, to include the balance, so that the grand total will be the result from the final operation of the machine, such grand total result also being 45 indicated by digit apertures. That is, the digit apertures irrespective of the total they represent, may in a single operation, assist the adding machine to take care of a balance when any further computations are to be 50 made by the machine, and since this is automatically accomplished, it is obvious that considerable time and labor will be saved compared to an ordinary adding machine.

55 My invention further aims to provide means for making tabulated computations

which may be embodied in or attached to an ordinary adding machine so that the printing outfit or equipment of the machine may be utilized for producing a readily discernible record, parallel to the digit record, which may be necessary when such record is to be used by those not familiar with the digit apertures. It is in this connection that the machine, to be hereinafter described, 60 may be equipped with a suitable printing outfit operable in synchronism with the punching instrumentality of my machine. 65

My invention further aims to combine an adding mechanism and a recording mechanism with a selector mechanism for controlling the operation of the adding mechanism, and the manner of combining all of these mechanisms permits of the adding and recording mechanisms being used independent 70 of the selector mechanism. Then again, the selector mechanism is associated with the adding mechanism so that the adding mechanism may be actuated to assist the recording mechanism in taking care of, or carrying 75 forward, the previous record in digits, and by having the adding mechanism operable independent of the selector mechanism, it is possible to add in additional matter to the 80 previous record. 85

My invention further aims to provide a machine in which a matrix, as an apertured card, permits of "feelers" automatically setting mechanisms in the machine so as to place the machine in a predetermined condition 90 preparatory to a recording performance.

In the above organization, the matrix or template is in the form of a card, sheet of paper or material that may be readily 95 punched to produce the digit apertures or apertures of any configuration representing a code, and in selecting apertures of a card in the machine, provision has been made for positioning the apertures so that the different 100 positions will represent different digits or codes, for instance, numbers or characters. A person familiar with the working of the machine may readily read a card, whereas a person unfamiliar with the code will be 105 unable to decipher the reading of the apertures in the card. To produce such apertures necessitates the use of punches or cutting instrumentalities, and these punches are characterized by being rotary as well as 110 reciprocatory, and by using a positive and reliable mechanism to operate the punches,

it is possible to produce sharp and accurately cut, predetermined positioned apertures, in the card beneath the punches.

The principal elements of the invention—namely, a machine body or casing; punches and the reciprocable operating mechanism thereof; automatic rotary setting mechanism for the punches; adding and power transmission mechanisms; actuators for the power transmission mechanism; selector mechanism and its relation to the adding mechanism; keyboard and release mechanisms; feelers and operating means of the selector mechanism; and clearing mechanism for the machine, will be hereinafter separately and specifically described in detail and operation, together with the novel arrangement and objects accomplished by the combinations of such devices and instrumentalities.

Reference will now be had to the drawings, wherein—

Figure 1 is a vertical, longitudinal, sectional view of the main portions of the adding machine;

Fig. 2 is a developed view of one of the feelers of the machine;

Fig. 3 is a horizontal sectional view of a portion of the machine taken on the line III—III of Fig. 1;

Fig. 4 is a similar view of a portion of the machine taken on the line IV—IV of Fig. 1;

Fig. 5 is a perspective view of resilient dogs forming part of the machine and associated with the keys thereof;

Fig. 6 is a vertical cross-sectional view of the machine, taken on the line VI—VI of Fig. 1, showing in front elevation the greater part of the tabulating mechanism;

Fig. 7 is a longitudinal sectional view of a portion of the machine taken on the line VII—VII of Fig. 6, and representing a continuation of Fig. 1;

Fig. 8 is a horizontal sectional view taken on the line VIII—VIII of Fig. 6;

Fig. 9 is a longitudinal view of a portion of the machine taken on the line IX—IX of Fig. 3, and showing the adding and power transmission mechanisms;

Fig. 10 is a plan of a portion of the card or sheet of paper containing digit apertures in accordance with this invention;

Fig. 11 is a cross sectional view of a portion of the machine taken on the line XI—XI of Fig. 1;

Fig. 12 is an enlarged vertical sectional view of a lifting device associated with each feeler of the machine;

Fig. 13 is a horizontal sectional view of the lifting device taken on the line XIII—XIII of Fig. 12;

Fig. 14 is a perspective view of a portion of the feeler showing its relation to a portion of an apertured card;

Fig. 15 is an enlarged bottom plan and section of a punch;

Fig. 16 is an enlarged longitudinal sectional view of the adding and power transmission mechanisms, and

Fig. 17 is a plan of a portion of the machine, showing the key board and a series of keys to be hereinafter considered when referring to the general operation of the machine.

In describing my invention by aid of the views above referred to, I desire to point out that the same are intended as merely illustrative of an example by which my invention may be put into practice, and I do not care to confine my machine to the precise construction and arrangement of parts, other than defined by the appended claims.

The general idea as to the length, height and breadth of the machine may be had by considering Figs. 1, 6 and 7, the latter figure being practically a continuation of the upper portion of Fig. 1. In the lower portion of the machine the adding selective, clearing and other mechanisms are located with the key board at the front part of the machine and the various operating levers at the right hand side thereof, while in the upper portion of the machine there is the tabulating mechanism and a portion of the tabulating mechanism overhangs a portion of the base of the machine, providing a throat in which a card or sheet of paper may be placed and shifted from time to time so as to be operated upon by the machine.

From Figs. 1, 6 and 7 it will be gathered that the machine body or casing may have extensions in different directions to accommodate a printing outfit, a card cabinet, an index system or appurtenances that will contribute to the usefulness of the machine; furthermore, the machine body or casing may represent a portion of some other machine.

Furthermore, with the operating cranks of the machine at one side thereof, I desire to suggest that these cranks or their equivalents may be successively operated, in timed relation, from a prime mover or suitable source of power, controlled by the operator of the machine.

The various organizations and machine elements heretofore referred to will be now described under separate captions, and attention directed to those figures of the drawings best showing each organization.

Cards. (Figs. 2, 10 and 14).

The portion of a card or sheet of paper A shown in Fig. 10, has a side edge thereof provided with positioning notches B so that this card may be correctly positioned in the machine to be punched. Transversely of the card is a series of digit apertures C and each aperture is circular with an inwardly projecting nib or lug D constituting the digit portion of the aperture according to its location about the circumference of the

aperture. The inwardly projecting nib is substantially semi-circular and consequently imparts a somewhat crescent shape to the aperture C, and in punching the aperture, 5 the position to be occupied by the nib D may be predetermined and a code devised for the different positions of the nib, so that one position of the nib will indicate one thing and another position of the nib another 10 thing. For instance, as indicated in Fig. 10, a position of the nib thirty-six degrees west of north may represent the numeral 9; eighteen degrees north of west, the numeral 8; eighteen degrees south of 15 west, the numeral 7; thirty-six degrees west of south, the numeral 6; due south, the numeral 5; thirty-six degrees east of south the numeral 4; eighteen degrees south of east the numeral 3; eighteen degrees north of 20 east the numeral 2; and thirty-six degrees east of north, the numeral 1. In other words, the circular aperture is divided into nib degrees representing nine numerals, characters or symbols of a code and with 25 the code understood it is possible to interpret or read the nib positions shown by the series of digit apertures. When a gap appears in the row of digit apertures it indicates naught or zero as designated in Fig. 30 10, with numbers 1, 2, 3 0 5 6 0 8 9 indicated by the digit apertures and such digits may represent a large number or dollars and cents, for instance \$1,230,560.89.

Assuming that \$5,346,572.31 is to be added 35 to the first sum of money, the card A is provided with another series of digit apertures E which are disposed in a transverse row contiguous to the first row of digit apertures C. The same punches employed for producing the digit apertures C are employed for producing the digit apertures E but the punches are partially rotated so that the nibs appearing in the digit apertures E will have positions indicating the sum of 40 \$6,577,133.20, this being the total of the two sums of money mentioned above. It is only necessary to compare the two rows of digit apertures to note that the nib position representing a number in one row corresponds to 45 the nib position of the same number in the other row.

With the card or sheet of paper A made of a durable material, the inwardly projecting nib D may be utilized for actuating purposes, and I here direct attention to the fact 50 that it is practically impossible to alter the digit apertures for misleading purposes.

Machine Body. (Figs. 1, 3, 4, 6, 7, 8, 11 and 17).

The machine body or casing includes, among other things, two side walls 1 and 2, an intermediate longitudinal partition 3, a front wall 4, provided with a wall extension 5, a top wall or table 6 having an in-

clined portion 7 on the wall extension 5, and the side walls 1 and 2 have the upper front edges thereof extended to meet the wall extension 5 so as to provide an inclosure overhanging the front portion of the 70 machine. The partition and walls thus far described provide the main compartments of the machine and above the top wall or table 6 is a tabulating compartment composed of side walls 8 and 9, a bottom wall 10, a front 75 wall 11, a top wall 12, a rear wall 13, a horizontal partition 14, and a vertical longitudinal partition 15 connecting the bottom wall 10 to the horizontal partition 14. By reference to Figs. 6 and 7 it will be noted 80 that the bottom wall 10 of the tabulating compartment is in spaced relation to the front wall or table 6 thereby providing a throat in which the card or sheet of paper A may be placed to be operated upon while 85 in the machine.

The inclined portion 7 of the top wall or table 6 has longitudinally disposed key slots 16, and further back in the top wall or table 6 are feeler openings or a slot 17 vertically alining with the feeler openings 18 in a transversely disposed feeler guide 19 mounted on the top wall 6, said feeler guide being in spaced relation to the top wall and having its front edge curved upwardly so 95 that the card A may be easily placed under the feeler guide.

To correctly position the card A with the digit apertures C in vertical alinement with the feeler openings 18 and 17, a longitudinally disposed guide 20 is mounted on the front wall 6 and provided with a lug or projection 21 (Figs. 1 and 17) adapted to engage in one of the notches B of the card A, the notches B being spaced for a predetermined 105 distance between the transverse rows of digit apertures in the card.

Adjacent the front upturned edge of the feeler guide 19 is a countersunk transversely disposed pad or cushion member 22 which 110 is suitably held within the top wall 6 beneath a series of punches operatable from the upper portion of the machine, said pad preventing injury to the cutting edges of the punches, which are adapted to produce 115 the row of digit apertures C.

Tabulating punches and reciprocable operating mechanism therefor. (Figs. 2, 6, 7, 8 and 15.)

In the tabulating compartment are slotted guides 23 cooperating with the partition 15 in supporting superposed staggeredly arranged transverse rack bars 24 meshing with pinions 25 on vertically disposed punch rods or shafts 26 rotatable and reciprocable in the bottom wall 10 and the horizontal partition 14. Some of the rack bars are wide compared to others, as shown in Fig. 8, so that the rack portions of said bars 120

will be in a common vertical plane, thereby permitting of the punch shafts 26 being placed in a common plane above the pad 22.

On the lower end of each punch shaft 26 is a head 27 (Fig. 15) and detachably connected to said head is a substantially cylindrical hollow punch member 28 having its lower end terminating in a feeling edge 29, and this feeling edge corresponds in shape

10 to one of the digit apertures C of the card A.

In Fig. 2 the feeling edge and its member have been developed and this view will again be referred to when considering the feelers of the machine.

15 Loose in the punch member 28 is an axial ejector 30 normally maintained in an extended position by the expansive force of a coiled spring 31 surrounding the shank or stem of the ejector, and the outer end of

20 the ejector conforms in shape to the feeling edge 29 of the punch member 28, so that the outer end of the ejector may enter the punch member 28 during a feeling or stamping action of said punch member. The ejector

25 recedes sufficiently to permit the punch member 28 to receive punched material from the card A, and this is accomplished with the card resting on the pad 22 of the top wall or cable 6. As the punch member 28

30 is elevated the ejector 30 discharges the waste material within the punch member and any suitable provision may be made for further removing the waste material from the top wall or table 6. With the

35 punch member 28 detachably connected to the head 27, it is possible to remove the punch member and sharpen the edges 29, from time to time, then again, it is possible to substitute another punch member there-

40 for so that the digit aperture to be produced by the punches may be changed from time to time.

The punch shafts 26, above the bottom wall 10, are provided with abutments 32 for

45 springs 33 encircling the punch shafts 26, between the bottom wall 10 and said abutments, and the expansive force of these springs maintains the punch shafts 26 normally elevated, with the heads 27 of said

50 punch shafts abutting the bottom wall 10. By reference to Fig. 7 it will be noted that there is sufficient clearance beneath the punch members 28 to permit the card A to be inserted and placed under the guide 19.

55 The upper ends of the punch shafts 26, above the horizontal partition 14, are slideable in and through tubular guides 34 carried by the lower face of a cross head 35, the cross head having its ends provided with

60 shoes slidable between guide rails 36, carried by the side walls 8 and 9. The upper face of the cross head 35, adjacent its ends has sets of apertured lugs 37 and pivotally connected to said lugs are bell cranks 38 pivotally supported on sets of brackets 39

extending inwardly from the walls 8 and 9. The bell cranks 38 have their hub portions 40 engaging cams or eccentrics 41 on a shaft 42, journaled in the walls 8 and 9, said shaft having an end thereof provided with an operating crank 43. When this crank is rotated, by hand or power, the bell cranks 38 are oscillated and the cross head 35 reciprocated between the walls 8 and 9.

On each of the punch shafts 26, above the partition 14, is a head 44 provided with an upstanding tooth 45 adapted to be engaged by the lower toothed or serrated end 46 of the tubular guide 34 which receives the punch shaft, and this tubular guide has a recess or zero notch 47 adapted to receive the tooth 45, when this zero notch vertically alines with the tooth, otherwise the tooth is engaged by the toothed lower edge of the tubular guide. With the tooth 45 alining with the zero notch 47 of the tubular guide 34, the cross head 35 may be lowered without actuating the punch shaft, consequently the punch or cutting instrumentality at the lower end of the shaft will not operate above the card placed on the pad 22. Such takes place when a zero is to be represented on the card A, and the gap or space left by the inactive punch may represent a dash or some symbol.

When the punch shaft 26 is partially rotated to move the tooth 45 out of alinement with the notch 47 of the tubular guide 34, then the lowered cross head 35 causes the tubular guide 34 to impinge against the tooth 45 and lower the punch shaft 26, causing the punch or cutting instrumentality at the lower end of said shaft to punch the card A and provide it with a digit aperture C. The tooth 45 and the teeth or serrations 46 at the lower end of the tubular guide 34 are of such contour that a positive engagement is insured between the tooth 45 and the tubular guide 34, such positive engagement preventing any shifting of the punch shaft 26 due to lost motion, and consequently the digit apertures C may be accurately cut and properly positioned in the card A.

Automatic rotary setting mechanism for the punches. (Figs. 6, 7 and 8.)

The means employed for reciprocating the punch shafts 26 having been described, reference will again be had to the rack bars 24 forming part of the rotary setting mechanism, by which the punch shafts are partially rotated to permit of the digit apertures being correctly positioned in the card A.

Those ends of the rack bars 24 confronting the side wall 8 are provided with side extensions 48 connected by coiled retractile springs 49 to the partition 15, and the retractile force of the springs 49 is adapted

to re-set the rack bars 24 after each actuation. The ends of the rack bars are connected to cables or flexible members 51 strained over sheaves 52 suitably supported from the front wall 11 and the rear wall 13, as best shown in Fig. 8. The cables or flexible members 51 extend downwardly through the top wall or table 6 and are attached to drums 54 rotatably supported about one end of a shaft 53 which is suitably fixed within suitable bearings of the side walls 1 and 2. The cables 51 are attached to the drums 54 so as to be wound thereon and the drums are disposed in parallelism with hollow hub portions 55 thereof telescoping one another on the stationary shaft 53. On account of this arrangement the drums 52 have hubs which vary in diameter and the arrangement of the hubs 55 affords a substantial bearing for the drums on the stationary shaft 53.

Adding and power transmission mechanism.
(Figs. 1, 3, 6, 7, 9 and 16).

25 Loose on the stationary shaft 53 are parallel closely assembled gear wheels 56 having side rims 57 (Fig. 7) and hollow hubs 58 with the hubs extending in an opposite direction from the side rims 57. The 30 hubs 58 telescope one another, similar to the hubs of the drums 54 and the hubs 58 are suitably coupled to the hubs 55 of the drums 54, for instance, as at 59, such connection permitting of the drums and gear wheels 35 being easily, quickly and properly assembled about the stationary shaft 53, so that a gear wheel is coupled to a drum to be operated in unison therewith. As best shown in Fig. 6 the drums 54 are assembled at one end of the stationary shaft 53 and the gear wheels 56 at the opposite end of said shaft, and with the side rims of the gear wheels abutting adjacent gear wheels, said side rims will afford bearings for adding rings 60 and segment gears 61, there being an adding ring 40 and a segment gear associated with each of the gears 56, and the adding rings are sandwiched between the segment gears 61 and the gears 56. The adding rings 60 are 45 pinned or otherwise fixed to the side rims of the gears 56, as at 62, and each adding ring has a beveled tooth 63, as shown in Figs. 7 and 9. Each segment gear 61 has a stop lug 64 diametrically opposite the 50 toothed portion and the stop lug 64 is adapted to engage a depending stop 65 carried by the top wall or table 6. The stop lug 64 is also adapted to engage a radially disposed stop pin 66, on the side rim 57, said stop pin 55 being in the path of the stop lug 64, as shown by full lines in Fig. 7 and by dotted lines in Fig. 16. As a result of this arrangement the segment gear 61 may be partially rotated, in a counter-clockwise direction, to 60 cause the stop lug 64 thereof to impinge

against the stop pin 66 and impart movement to the side rim of a gear 56, and besides the gear 56 being moved by the segment gear 61, the adding ring 60 will be also shifted in unison with the gear 56, by reason 70 of its pinned connection with said gear.

Before considering the adding feature of my machine, it is thought best to briefly rehearse the mechanism actuated by the gears 56. Since the machine has been designed 75 for producing nine digit apertures in the card A, there must necessarily be nine punches, nine rack bars for rotating the punches, nine drums for the flexible members, and nine of the gear wheels 56 with 80 an adding ring and segment gear associated with each of the gear wheels 56. So, in order that the adding feature may be applicable to each of the gear wheels 56, an adding mechanism is located adjacent each 85 gear wheel.

Mounted in the side walls 1 and 2 and extending transversely of the machine are rods 67, 68, 69 and 70, and slidable on the rod 68 and having a slotted connection with the rod 69 are tiltable arms 71 corresponding in number to the adding rings 60. The tiltable arms 71 are spaced apart on the rod 68 by spacers 72 and each tiltable arm has a beveled tooth 73 adapted to be engaged and elevated by the beveled tooth 63 of the adding ring 60.

Pivoted on the rod 67 and extending over the tiltable arms 71 are levers 74. The forward ends of the levers 74 are connected 100 by coiled retractile springs 75 to the tiltable arms 71, and when the tiltable arm is elevated by the beveled tooth 63 of an adding ring 60, the rear end of the tiltable arm elevates the forward end of the lever 74, 105 against the action of the spring 75, causing the rear end of the lever 74 to be lowered. This may be best understood by reference to Fig. 9, where the purpose of the tiltable levers 74 may be further understood. Pivot- 110 ed on the rear end of the lever 74 is a pawl 76 having its upper end connected to the end of the lever 74 by a coiled retractile spring 77, and the retractile force of this spring maintains a stop 78 of the pawl normally 115 in engagement with the lever 74, so that the lower end of the pawl 76 is in position to engage one of the gears 56 when the pawl is lowered. When one of the tiltable arms 71 is tilted it is restored to normal position by 120 the retractile force of a coiled spring 79 connecting the tiltable arm to a rod 80 extending transversely of the machine and supported by the side walls 1 and 2.

Connecting the side walls 1 and 2 of the 125 machine body and extending transversely thereof in proximity to the gear wheels 56 is another rod 81, and pivoted on said rod are detents 82 normally engaging the gear wheels 56 to hold said gear wheels in ad- 130

justed positions. The detents 82 are connected by coiled retractile springs 83 to the rod 80, and the retractile force of the springs 83 is slightly greater than the retractile force of the springs 49 associated with the rack bars 24, so that after the gear wheels 56 have been forcibly adjusted to shift the rack bars 24, against the action of the springs 49, the pivoted detents 82 will hold said gear wheels in the positions to which they are adjusted.

Actuators for the power transmission mechanism. (Figs. 1, 3 and 6).

15 Fulcrumed on the ends of the stationary shaft 53 are bell cranks 84 having arms thereof connected by transverse rods 85 and 86, the rod 86 being normally under portions of the pivoted detents 82, as shown in Fig. 9 so that the rod 86 may, upon actuation of the bell cranks 84, shift the detents 82 out of engagement with the gear wheels 56, thereby permitting said gear wheels to assume normal position.

20 25 Rotatable on the rod 85 are pinions 87 meshing with the gear wheels 56 and pinions 88 meshing with the segment gears 61, and these pinions loosely ride in engagement with the gear wheels 56 and the segment gears 61 when the bell cranks 84 are actuated to clear the machine.

To maintain the pinions 87 and 88 in operative relation to the gear wheels 56 and segment gear wheels 61, the bell cranks 84 have stop lugs 89 engaging studs 90 on the walls 1 and 2, and said bell cranks are connected to the walls by coiled retractile springs 91.

Since the gear wheels 56 are located at one end of the stationary shaft 53 and the partition 3 cut away, as at 92, to provide clearance for the adding and power transmission mechanism, it is only necessary to locate the actuators between the wall 1 and the partition 3. Connecting the wall 1 and the partition 3 are transverse rods 93 and 94 and slidable on these rods in a horizontal plane are actuator racks 96 for the pinions 87 of the gear wheels 56 and actuator racks 95 for the pinions 88 of the segment gear 61, said actuator racks being slotted, as at 97, to provide clearance for the rods 93 and 94. The actuator racks 95 are of a rather peculiar shape by having the rear ends thereof terminating in stepped or notched heads 98 and spring supporting rods 99. The rear ends of the actuator racks 95 rest on a fixed transverse support 100 connecting the wall 1 and the partition 3, and adjacent this support, the rear ends of the actuator racks 95 have stop lugs 101, the purpose of which will hereinafter appear.

The spring supporting rods 99 of the actuator racks 95 extend through a depending support 102 of the top wall or table 6,

and on said supporting rods are coiled expansion springs 103 engaging abutments 104 of said rods, so that the expansive force of the springs 103 may constantly tend to pull the actuator racks 95 rearwardly.

70 The actuator racks 96 have the forward ends thereof enlarged to provide keepers 104, depending apertured lugs 105, and laterally extending stops 106. The depending apertured lugs 105 are connected by coiled 75 retractile springs 107 to a transverse rod 108 connecting the wall 1 and the partition 3. The purpose of the keepers 104 and stops 106 will appear in connection with the key board and releasing mechanism to be hereinafter described.

Selector mechanism and its relation to the adding mechanism. (Figs. 1, 3, 6 and 7).

The spring supporting rods 99 of the actuator racks 95 extend through a transverse slotted guide member 109 supported from the lower face of the top wall or table 6, and this slotted guide member is in proximity to the stepped heads 98 of the actuator racks 95 with the slots in said guide member of sufficient depth to provide clearance for the stepped heads 98.

Slidable in the slots of the guide member 109 are two-part selector members 110 which confront the stepped heads 98 and these selector members are adapted to be vertically reciprocated in the guide member 109 and positioned to provide abutments and stop the rearward movement of the stepped heads 98, thus limiting the rearward movement of the actuator racks 95. By reference to Fig. 1, it will be noted that the stepped heads have stepped portions or shoulders corresponding in number to the punches of the tabulating mechanism and the digit apertures C to be produced thereby, and by the selector members 110 limiting the rearward movement of the actuator racks 95, the rotation of the gears 61 is predetermined, and consequently the rotation of the punch shafts 26.

Pivotedly connected to the rear ends of the slidable selector members 110 are hangers 111 and pivotedly connected to said hangers and disposed practically in parallelism are fulcrumed levers 112 extending through slots of the guide member 109. The levers 112 are fulcrumed on transverse rods 113 connecting the wall 1 and the partition 3. These levers will again be referred to when considering the feelers and the operating means for the selector members.

Key board and releasing mechanism. (Figs. 1, 3, 5 and 17).

125 The partition 3 terminates at the front wall 4 of the machine body, without extending into the forward overhanging portion of said machine body, and connecting the side walls 1 and 2 is a transverse 130

rod 114. Pivoted on this rod are a series of key members 115 having vertical extensions projecting through the key slots 16 in the inclined portion 7 of the top wall 5 or table 6, and each key member has a numbered or designated head or finger piece 116, as best shown in Fig. 17. Each key slot provides clearance for ten key members so that there are ninety key members for 10 the key board, and each key member has a depending finger 117 adapted to be placed in the path of the stops 106 of the actuator racks 96. The forward end of each key member 116 has a rearwardly extending arm 118, and these key member arms are connected by coiled retractile springs 119 to a transverse rod 120 supported by the wall 1 and a forwardly extending bracket 121 of the partition 3. The retractile force 15 of the springs 119 hold the arms 118 normally elevated against a transverse rod 122 connecting the walls 1 and 2 of the machine body, and consequently the key members 115 are maintained normally elevated ready 20 to be depressed.

The rear end of each arm 118 is frictionally engaged by a dog 123 and the dogs are mounted in a transverse holder 124 suitably secured to the wall extension 5. The dogs 25 123 are resilient and the ends of the arms 113 may ride downwardly on the dogs, and be held in lowered positions by said dogs, so that the key members 115 may have the fingers 117 thereof set in the path of the 30 stops 106 of the actuator racks 96.

Connecting the walls 1 and 2 of the machine body is a transverse shaft or rod 125 and pivotally mounted on this rod are latches 126 having the rear ends thereof engaging keepers 104 of the actuator racks 40 96. The forward ends of the latches 126 are connected by coiled retractile springs 127 to a transverse rod 128 connecting the bracket 121 and the side wall 1 of the machine body.

Rotatably supported by the side walls 1 and 2 is a cam shaft 129 which has one end thereof projecting through the side wall 2 and provided with an operating crank 130. Equally spaced about the periphery of the cam shaft 129 are cams 131 corresponding in number to the latches 126 and when the cam shaft 129 is rotated the cams 131 are adapted to depress the forward ends of the 50 latches 126 and cause the rear ends of said latches to release the keepers 104 of the actuator racks 96, so that said actuator racks may move rearwardly, under the influence of the springs 107, and actuate the pinions 87 and the gear wheels 56.

Feelers and operating means for selector mechanism. (Figs. 1, 4, 7 and 11 to 14 inclusive).

65 Connecting the side wall 1 and the par-

tition 3 below the support 100, are additional superposed supports 132 provided with worm screwthreaded openings for worms 133, each worm being rotatably mounted in a frame or cage 134 which is 70 slidably held by the support 132. The supports 132 extend through the cages 134 and the rear edges of the cages, at the lower ends thereof, have pin and slot connections 135 with the forward ends of the levers 112, 75 so that said levers will be operated as the cages 134 are raised and lowered.

Extending through the worms 133 are the rectangular portions 136 of feeler shafts 137, and each feeler shaft has a collar 138 80 engaging the top of the cage 134 so that said cage will be lowered simultaneously with its feeler shaft.

The lower ends of the feeler shafts 137 extend through a yoke 139 having its ends 85 provided with shoes 140 slidable between vertically disposed guides 141, carried by the confronting faces of the wall 1 and partition 3. The lower ends of the feeler shafts 137 are held relative to the yoke 139 90 by nuts 142 and collars 143 loose on the feeler shafts 137 above the yoke 139 said collars being yieldably held in engagement with the yoke by coiled compression springs 144 encircling the feeler shafts 137 and abutting fixed collars 145 on said feeler shafts.

Loosely connected to the ends of the yoke 139 for raising and lowering said yoke are side arms 146 pivotally supported, as at 100 147 from the confronting faces of the wall 1 and the partition 3. The forward ends 105 of the arms 146 are pivotally connected as at 148, to eccentric straps 149 on eccentrics 150 mounted on a transverse shaft 151. The 105 shaft 151 extends through the partition 3 and is rotatably supported by the side walls 1 and 2 with the end of the shaft projecting from the side wall 2 and provided with an operating crank 152. When the crank 110 152 is rotated the arms 146 are oscillated and the yoke 139 is raised and lowered. Those feeler shafts which are free to be raised by the yoke 139 will be shifted upwardly, but those feeler shafts which encounter obstacles may remain stationary by the yoke 139 sliding on the feeler shafts 137 against the action of the springs 144. The purpose of this yieldable connection between the feeler shafts 137 and the yoke 120 139 will hereinafter appear.

Slidable in the guides 141 are shoes 153 of a transverse latch bar 154, and this latch bar is adapted to be engaged by the stop lug 101 of the actuator rack 95. The shoes 153 125 are provided with stop brackets 155 adapted to engage stop pins 156 on the confronting faces of the wall 1 and the partition 3, and said stop brackets are connected by coiled retractile springs 157 to the wall 1 and the 130

partition 3 so that the retractile force of the springs may retain the latch bar 154 lowered in the path of the stop lugs 101 of the actuator rack 95, thus holding the actuator racks against the action of the springs 103. The transverse latch bar 154 may be elevated to release the actuator racks 95 by the upper ends of the shoes 140 of the yoke 139 impinging against the lower ends of the 10 shoes 153 of the transverse latch bar 154. This takes place against the action of the springs 157 and said springs are adapted to restore the latch bar to its normal position for holding the actuator racks 95. With the 15 latch bar 154 and the stop lugs 101 beveled, as shown in Fig. 1, the actuator racks 95 may be shifted under said latch bar with said latch bar snapping behind the stop lugs 101 to hold the actuator racks 95 in retracted positions.

The feeler shafts 137 vertically aline with the openings 17 in the top wall or table 6, and the upper end of each feeler shaft has a cylindrical feeler 158, best shown in Fig. 25. The upper end of the feeler 158 terminates in a nose 159 so that it may readily enter one of the digit apertures C, and the cylindrical body of said feeler has a spiral way or cam surface 160 with its lower end 20 communicating with a longitudinal groove 161. With the feeler entering the digit opening C the spiral way 160 receives the nib D and said nib bears against the walls of the spiral way 160 and causes the feeler 158 to 25 be rotated until the nib enters the upper end of the groove 161 when said feeler ceases to rotate but may move vertically in the digit aperture C.

When the feeler shafts 137 are raised by 30 the yoke 139, the rectangular portions 136 of said shafts slide through the worms 133 until the feelers 158 start to revolve, when movement is imparted to the worms 133 and as these worms operate in the stationary support 132 the cages 134 will be elevated to 35 actuate the selector members 110. As the worms 133 are driven by the feeler shafts 137 the upper ends of the worms shift away from the supports 132, and in order that 40 the worms will always be correctly positioned, relative to supports 132 and thus cause the feelers 158 to be correctly positioned relative to digit apertures, the upper end of each worm 133 has a radially disposed pin 179 adapted to ride into and out 45 of engagement with a stationary pin 180 on the support 132. The pins 179 and 180 will insure each feeler head 158 being correctly positioned for the upper end of the inclined 50 way or cam surface 160 to impinge against the nib D of the card A. The inclined way or cam surface 160 has been developed in Fig. 2 of the drawing, and by reference thereto it will be noted that such spiral inclined way is opened so that as the feelers

are raised different parts of the inclined way 160 may impinge against a nib. The inclined way is practically divided into nine divisions of one revolution, and assuming that a feeler is to feel out the numeral 2, it 70 will be elevated a greater distance than a feeler for the numeral 7, before a rotary movement is imparted thereto. For instance, those feelers representing low numerals, as 1, 2, 3, will have a greater distance to travel 75 vertically before being rotated than those feelers representing the numerals 7, 8 and 9. In consequence of this arrangement of the open inclined ways 160, the feelers receive 80 different degrees of rotation and after the feeler has been properly adjusted its vertical movement is permitted by reason of the vertical groove 161. The distance between the lower ends of the shoes 153 and the upper ends of the shoes 140 is a little greater than 85 the vertical dimension of the feeler slopes or ways, so that while the grooves 161 of the feelers are passing through digit openings, the shoes 140 may raise the shoes 153 and the latch bar 154.

Clearing mechanism for the machine. (Figs. 1, 3, 7 and 9).

The bell cranks 84 have been described as pivoted on the shaft 53 with the rod 86 extending under the detents 82 to shift 90 said detents and release the gears 56, so that the gears 56 and elements actuated directly or indirectly thereby may be restored to normal position. In order that the bell cranks may be actuated, one of the bell 95 cranks 84 has a handle 162 protruding through an opening provided therefor, in the top wall or table 6 of the machine. This handle may be pushed rearwardly to 100 shift the detents 82, and said handle also constitutes a part of the clearing mechanism for such key members 115 as has been depressed and set, with the dogs 123 holding the arms 118.

Pivottally connected to each bell crank 84 is a reach rod 163 and the lower ends of the reach rods are pivotally connected to cranks 164 on the ends of a rock shaft 165 journaled in the side walls 1 and 2 or 110 bearings carried thereby. On the rock shaft 165 is a long cam member 166 which may be swung against the dogs 123 to shift the dogs out of engagement with the arms 115, thereby permitting the retractile force 115 of the springs 119 to restore the key members 115, to normal elevated position. The cam member 166 is adapted to ride into depressions 167 of the dogs 123 and temporarily hold said dogs stressed while the key 120 members 115 are actuated by the springs 119, also while other parts of the machine are being cleared.

Considering the actuator racks 95 and 96, a rod 168 extends through the for- 125

wardmost slot 97 of said racks, and the ends of the rod 168 extend through the upper slotted ends of arms 169 pivotally supported, as at 170 on the confronting 5 faces of the wall 1 and the partition 3. The lower ends of the arms 169 are pivotally connected to eccentric straps or extensions 171 thereof and said eccentric straps are mounted on eccentrics 172 carried by a 10 transverse shaft 173 supported by the side walls 1 and 2 and extending through the partition 3. One end of the shaft 173 has an operating crank 174 and when said shaft is rotated by said crank, the arms 169 shift 15 the rod 168 forwardly and said rod carries with it the actuator racks 95 and 96. The actuator racks 95 will be shifted forwardly until the latch bar 154 engages the stop lugs 101 of the actuator racks 95 and the 20 actuator racks 96 will be shifted forwardly until the keepers 104 ride under the latches 126 and are held thereby, as shown in Fig. 1.

This clearing operation having been performed the dogs 123 which have been previously stressed may resume normal position to engage the ends of the arms 118 of the key members 115, as shown in Fig. 1, and the mechanism employed for this purpose consists of an arm 174^a having its forward end pivotally connected to another crank 175 of the rock shaft 165. The rear end of the arm 174^a is bifurcated or slotted, as at 176 to receive the shaft 173 and said arm has a side extension 177, adjacent the shaft 173, to be engaged by a cam or crank 178 on the shaft 173. When the shaft 173 is rotated the cam or crank 178 impinges against the side extension 177 of the arm 40 174^a, and said arm rocks the shaft 175, thereby moving the cam 166 out of the dog depressions 167, and the dogs are permitted to again engage the arms 118 of the key members 115.

General operation.

From time to time the operation of certain organizations of the machine have been described, and with the machine cleared, I 50 will now assume that the card A has previously received the digit apertures D representing the sum of \$1,230,560.89, as represented by the top row of apertures in Fig. 10 of the drawing.

The card A is placed under the feeler guide 19 with the notch B, opposite the row of apertures C, receiving the positioning member or lug 21 of the guide 20. Then the digit aperture C will be in vertical alignment with the feeler openings 17 and 18 to permit of the feelers 158 moving upwardly through the table 6, the apertures C and the feeler openings 18 of the guide 19; it being understood that the bottom wall 10 of the tabulating mechanism is located a sufficient

distance above the top wall or table 6 to provide clearance for the upward movement of the feelers 158. The bottom wall 10 may be slotted or apertured to permit of the feelers entering the tabulator compartment 70 just so the feelers do not strike the lowermost rack bars 24 therein. To indicate such distances and permit of various parts being shown in the drawings as large as possible, the various views have been broken away. 75

With the card A in position, the crank 152 is turned to raise the yokes 139, and cause the feeler shafts 137 to travel upwardly, and as pointed out under the caption relating to feelers, the feeler shafts 137 80 will be shifted upwardly providing there is a digit aperture to receive each feeler. In the present instance there are two spaces, representing naught, which are not apertured therefore two of the feelers will remain stationary, while seven feelers travel through the cipher apertures of the card. The feelers will eventually encounter the nibs D of the digit apertures and will be partially rotated thereby, casing the worms 90 133 to elevate the cages 132, shift the levers 112, and adjust the selector members 110 in the slotted guide member 109. This takes place on the initial upward movement of the feeler shafts 137 and eventually the 95 shoes 140 impinge upon the shoes 153 of the latch bar 154, causing said latch bar to release all of the actuator racks 95. These racks being under the influence of the springs 103 will be shifted rearwardly until the stepped or shouldered portions of the heads 98 impinge against selector members 110. Since two of the selector members have not been actuated, two of the actuator racks 95 will be retained in normal position 100 or approximately so as the uppermost shoulders of the heads 98 are at the inactive selector members 110. As the other selector members have been adjusted in the slotted guide member 104 the remaining 105 110 seven actuator racks will assume different positions, and, figuratively speaking, represent the numerals 1, 2, 3, 5, 6, 8, and 9 such shoulders so designated on Fig. 1 engaging the shifted selector members 110. 115

As the released actuator racks 95 move rearwardly said racks impart movement to the pinions 88 meshing with the segment gears 61, and said segment gears are rotated, each a prescribed number of degrees. 120 The partial rotation of the segment gears 61 is transmitted to the drums 54 by virtue of the hub portions 58 and 55, and the drums 54 pull on the cables 51 and shift the rack bars 24 against the action of the springs 49, 125 The rack bars 24 meshing with the pinions 25 cause the punch shafts 26 to be rotated and position the punch members 28 in accordance with the digit apertures of the card A. If the positioned punches were to be 130

employed to aperture a card the series of apertures produced by the punches would be the same as in the top row of apertures in the card A. The punches, however, after being adjusted by rotation, remain dormant for the time being.

The next operation is that of punching or depressing the finger pieces 116 of the key members 115 in accordance with the sum to be added, which according to the present example, is \$5,346,572.31. In operating the key board, the longitudinal rows of keys are successively used, the keys one, three, two, seven, five, six, four, three, five, being successively punched in their order and as the key members 115 are depressed the arms 118 of said key members are engaged and held by the dogs 123, thus placing the fingers 117 of the key members 115 in the path of the stops 106 of the actuator racks 96.

The next operation is that of rotating the cam shaft 129, so that cams 131 thereof will elevate the latches 126 and release the actuator racks 96. These actuator racks are shifted rearwardly, under the influence of the springs 107, until the stops 106 of said racks abut the fingers 117, the position of said fingers defining the movement of the racks 96. The racks, however, have shifted sufficiently to operate the pinions 87 of the gears 56 and said gears will transmit power to the rack bars 24, so that said rack bars may further rotate the adjusted punch shafts 26.

35 The first punch shaft at the right hand side of Fig. 6, having been adjusted to take care of the nine cents, represented by the first digit aperture, at the right hand side of the card A, must be further adjusted to include the one cent to be added thereto, and this means that the first punch shaft must be rendered inactive to leave a blank space on the card representing naught, and that "one" must be carried to the next column and added in with "eight" plus "three".

The segment gear 61 having been actuated to take care of the "nine" by the selector mechanism, depression of the key "one" causes the gear 56 to be further rotated and the first punch shaft is actuated to place the tooth 45 in vertical alinement with the notch 47 in the tubular guide 34 associated with said punch shaft, consequently when the cross head 35 is lowered, it will not depress the first punch shaft but allow it to remain dormant, so that no aperture is punched in the card A. This leaves the blank space on the card indicating naught.

60 "One" must, however, be carried into the next column and the second punch shaft, from the right in Fig. 6, is further adjusted to take care of the "one". This has been accomplished by the pinned adding ring of the previously rotated gear 56 having had its beveled tooth 63 brought

into engagement with the tiltable arm 71 above it, causing said tiltable arm to actuate the lever 74, swing the pawl 76 into engagement with gear 56, next to the previously rotated gear, and turn the second gear 56 to an extent that the second punch shaft is readjusted to take care of "one", before the same gear has been set in motion for "three" to complete the addition.

The addition for the second column necessitates carrying "one" over into the third column and, when necessary, the carrying over is accomplished by the tiltable arm 71, lever 74, pawl 76 and gears 56, just as in the first column. It is thought unnecessary to rehearse the entire setting of the punch shafts 26 for the complete sum of \$5,346,572.81, in addition to the original setting of the punch shafts, and as soon as the punches have been properly set the crank 43 is operated to lower the cross head 35 and cause the tubular guides 34 thereof to depress the punch shafts 26. As the punch members 28 encounter the card A the second row of digit apertures C are produced, representing the sum of \$6,577,133.20, and the material removed from the digit apertures is eventually ejected from the punch members 28 by the ejectors 30.

If any further sums are to be added to the total, the card A is advanced on the table 6 so that the feelers may enter the digit apertures E, but before the selector mechanism is placed in operation, the machine is cleared to permit of the various mechanisms assuming normal position.

What I claim is:—

1. Means for tabulating by a system including a card having apertures representing an initial computation and adapted to have apertures made therein representing an additional computation, comprising card aperturing means, feelers adapted to enter the card apertures and have a rotary movement imparted thereto by said card to adjust said card aperturing means, selective means adapted to further adjust said card aperturing means to include an additional computation, and means adapted to operate said card aperturing means to aperture the card to represent the initial and additional computations.

2. Means for tabulating by a system including a card having apertures representing an initial computation and adapted to have apertures made therein representing an additional computation, comprising adjustable card aperturing means, normally retracted spring operated actuators controlling said card aperturing means, a latch bar adapted to release said actuators, and feelers adapted to enter the apertures of said card and successively adjust said card operating means and actuate said latch bar to release said actuators.

3. Tabulating means as in claim 2, characterized by said card aperturing means being adjustable by rotation, and said feelers being rotated in said card apertures to adjust said card aperturing means.
4. Means for tabulating by a system including a card having apertures representing an initial computation and adapted to have apertures made therein representing an additional computation, comprising adjustable card aperturing means, an adding mechanism adapted to adjust said card aperturing means, spring operated actuators adapted to operate said adding mechanism, means holding said actuators inactive, means adapted to release said actuator holding means to permit said actuators to operate said adding mechanism, and manually operated means adapted to be set to limit the operation of said actuators.
5. Tabulating means as in claim 4 characterized by said manually operated means including keys adapted to be depressed and temporarily held, and additional means adapted to simultaneously release the held keys and clear said adding mechanism and said adjustable card aperturing means.
6. Tabulating means as in claim 4 characterized by and manually operated means includes keys and dogs for temporarily holding said keys in the path of said actuators.
7. The combination of a tabulating mechanism, adding and power transmission mechanisms for adjusting said tabulating mechanism, actuators for the adding mechanism, actuators for the power transmission and selective means for each actuator determining the adjustment of said tabulating mechanism, said selective means including latches for holding said actuators, and keys to limit the action of said actuators.

In testimony whereof I affix my signature in presence of two witnesses.
